UNITED STATES PATENT OFFICE.

JOHN A. LIST, OF PHILADELPHIA, PENNSYLVANIA, ASSIGNOR TO GOODMAN BROS. & HINLEIN, OF PHILADELPHIA, PENNSYLVANIA, A FIRM.

BRAID-KNITTING MACHINE.

Application filed June 20, 1923. Serial No. 646,552.

To all whom it may concern:

Be it known that I, JOHN A. LIST, a citizen of the United States, residing in Philadelphia, Pennsylvania, have invented certain

5 Improvements in Braid-Knitting Machines, of which the following is a specification.

My invention relates to certain improvements in knitting machines for knitting and fulling braids.

10 One object of my invention is to design the mechanism so that the fulled portion of the braid will not be flattened as it passes through the machine, but will retain its original shape.

15 A further object of the invention is to design the mechanism so that one, or more stitches can be formed at the loops of the braid, giving the rounded effect shown in the drawings.

20 In the accompanying drawings:

Fig. 1 is a transverse sectional view of my improved machine for knitting braid;

Fig. 2 is a plan view of a portion of the machine;

25 Fig. 3 is a perspective view;

Fig. 4 is a detached perspective view of the braid guide;

Fig. 5 is a face view of the braid;

Fig. 6 is a side view of the same;

30 Fig. 7 is a perspective view of the braid;

Fig. 8 is a view of the back of the braid;

Figs. 9 and 10 are views illustrating different forms of braid; and

35 Fig. 11 is a view of a modification of the braid guide.

Referring to Figs. 5, 6, 7 and 8, which illustrate the fashioned, fulled braid, 1 is a strip of woven ribbon. 2, 2 are the knitted side members, which are knitted onto the edge of the ribbon at intervals. The spaces between the points 3 of attachment are fulled so as to form tubular, raised portions 4, which give the unique effect shown in the drawings.

45 Referring to Figs. 1, 2 and 3, which illustrate the machine for making the braid, 5 designates the needle bar of a knitting machine, having grooves 6 for the latch needles 7. These latch needles are actuated in the manner common to knitting machines.

50 8 designates a longitudinal bar carrying the ribbon guide 9. 10 designates the plate bar, which carries guides 11 for the warp threads 2^a. 13 designates the loopers that

are mounted on bars 14. These loopers have 55 eyes through which the warp threads 2^b pass to the needles, as clearly shown in Fig. 1.

The ribbon guide plate 9 is preferably made as shown in Fig. 4, and has a flat portion 15 in which is a transverse slot 16. The guide plate back of the slot is reduced in width to allow for the free movement of the needles. On the reduced portion is a cylindrical guide 17 through which the ribbon passes to the slot 16. The cylindrical guide 17 is less in width than the ribbon, but the slot is of a width to allow the ribbon to pass therethrough in a flat condition. By making the guide 17 narrow, the needles 60 are allowed to form one or more stitches under the looped portions of the ribbon, as shown in Fig. 9, giving the rounded effect 65 shown in the drawings. On the back of the guide plate is a bar 18, which is hooked to 70 encircle a screw 19 that is secured to a plate 20, which is attached to the bar 8.

21 designates a bar that is located at the top of the needle bar and in close proximity to the needles for forming the looped, 80 raised portion 4 of the ribbon. This bar is carried by a suitable support.

The ribbon 1 is fed through the round guide 17 and then through the slot 16 in the guide plate 9 and over the bar 21. The warp 85 threads 2^a are fed through the guides 11 and the threads 2^b are carried by the loopers 13. These loopers move back of the needles to carry the thread beyond the needles, after which they are shogged to wrap the thread 90 around the needles. They are then moved forward so that the hooks of the needles will draw the threads down to form stitches on each side of the ribbon. One set of stitches passes through the edges of the ribbon and 95 under the raised portion, while the other set of stitches is formed beyond the edge of the ribbon, as illustrated in Fig. 5. The bases of the looped portions of the ribbon are spaced apart so that the loops will retain their 100 shape.

In Figs. 5, 6, 7, and 8, the loops are illustrated at equal distances apart. In Fig. 9, the loops are illustrated as arranged in groups of three. It will be understood that the loops may be arranged in many different ways to produce various effects.

By contracting the ribbon at the knitting

point, one or more stitches can be formed under the loop at each side thereof, which produces the fullness desired.

In Fig. 10, three stitches are formed under each loop. In Fig. 11, a modification of the guide is shown, in which two guide arms 17^a project from the narrow portion of the plate 9^a, contracting the ribbon to allow for the passage of the needles.

10 It will be understood that while I have shown a single guide and a single set of needles, the guide and needles are duplicated throughout the length of the machine, by means of which several braids are formed 15 simultaneously.

I claim:

1. The combination in a machine for forming looped braid, of needles; and a guide having a flat guiding portion for a ribbon 20 and having a contracted portion less in width than the flat guiding portion, said contracted portion being on a line with the needles.
2. The combination in a braid knitting machine, of a needle bar; thread guides; and a ribbon guide extending between two sets of needles, the guide having a slot 25 therein for a ribbon to pass therethrough in a flat condition and having a portion on a line with the needles less in width than the slot.

3. The combination in a braid knitting machine, of a needle bar; two sets of needles; guides for the threads forming the knitted stitches; a ribbon guide having a flat portion extending between the two sets of needles; said flat portion being slotted for the passage of the ribbon; and a cylindrical guide narrower than the slot and the space between the needles through which the ribbon passes prior to its having the knitted loops secured thereto.

4. A ribbon guide plate having a transverse slot of a width to allow a ribbon to pass therethrough in a flat condition, the 45 guide plate back of the slot being narrow to allow for the movement of knitting needles; and means, on the narrow portion of the plate, for contracting the ribbon to allow it to clear the needles.

5. A ribbon guide for a braid-knitting machine, the same consisting of a plate slotted for the passage of a ribbon in a flat condition, the guide plate back of the slot being narrow to allow for the movement of the 55 knitting needles; a cylindrical guide on the narrow portion of the plate for contracting the ribbon to allow it to clear the needles; and means by which the guide is attached to a knitting machine.

JOHN A. LIST.
